UNITED STATES PATENT OFFICE.

BENJAMIN D. SKIDMORE, OF NEW YORK, N. Y.

IMPROVEMENT IN WINDOW-SASH FASTENERS.

Specification forming part of Letters Patent No. 38,609, dated May 19, 1863.

To all whom it may concern:

Be it known that I, BENJAMIN D. SKIDMORE, of the city, county, and State of New York, have invented a new and Improved Window-Sash Fastening; and I do hereby declare that the following is a full, clear, and exact description of the same, reference being had to the accompanying drawings, making a part of this specification, in which—

Figure 1 is a vertical central section of my invention applied to a window, taken in the line $x-x$, Fig. 2, the window being also bisected. Fig. 2 is a front view of the same.

Similar letters of reference indicate corresponding parts in the two figures.

This invention relates to a sash-fastening of that class which are placed at the center of the upper cross-rail of the lower sash, and which are designed for keeping the sashes or locking the same in a closed state only.

The object of the invention is to obtain a fastening of the class specified, which may be unfastened by an upward pressure, the same which is employed to raise the lower sash, and thereby avoid the inconvenience of employing both hands in raising the sash, or two manipulations, as hitherto required—one to unlock or release the sashes, and the other to raise the lower one.

To enable those skilled in the art to fully understand and construct my invention, I will proceed to describe it.

A represents the lower, and B the upper, sash of a window, constructed and arranged in the usual way, and C is a case, of rectangular or other suitable form, which is secured to the center of the upper cross-rail, a , of the lower sash, A. Within this case C a slide bolt, D, is fitted over a suitable guide, b, and said bolt is provided with a pendent bar, c, between which and the front end of the case C a spiral spring, D', is placed, one end of the spring being attached to the bar c, and the other end to the front part of a pendant, e', attached to

guide b, as shown in Fig. 1. This spring has a tendency to keep the front end of the bolt D out from the case, and the under side of the front part of the bolt is rounded or beveled, as shown at d, so that it may catch into a nosing, e, at the center of the lower cross-rail, f, of the upper sash, B, when the lower sash, A, is shoved down.

E represents a bent lever, which is fitted in the case C on a proper fulcrum, b, back of the bolt D. The upper end of this lever is connected by a rod, g, with the back end of the bolt D, and to the lower end of the lever E there is attached by a pivot, h, a pendent rod, F, which passes through the center of the cross-rail a.

From the above description it will be seen that by pressing upward the rod F the bent lever E will be actuated, its upper part thrown back, and the bolt D drawn back and out from the nosing, so that by continuing the upward pressure the lower sash may be raised. As soon as the rod F is relieved from the upward pressure of the hand the spring D' will throw out the beveled end of the bolt D, and when the sash is lowered the bolt D will engage itself with the nosing e, owing to the beveled end d of the bolt D. Thus it will be seen that by this simple arrangement the lower sash may be released from its fastening and raised with the application of one hand only and by a single operation or manipulation.

Having thus described my invention, what I claim as new, and desire to secure by Letters Patent, is—

The combination of the slide-bolt D, spring D', lever E, and pendent rod F, all arranged in connection with the case C and nosing e, to operate as and for the purpose set forth.

BENJN. D. SKIDMORE.
